UNITED STATES PATENT OFFICE

TOM NUTTALL, OF FARNWORTH, NEAR BOLTON, AND SYDNEY ALFRED SHORTER, OF DIDSBURY, MANCHESTER, ENGLAND; SAID SHORTER ASSIGNOR TO THE BRITISH COTTON INDUSTRY RESEARCH ASSOCIATION, OF MANCHESTER, ENGLAND, A BRITISH ASSOCIATION

HOPPER BALE OPENER, HOPPER FEEDER, AND LIKE APPARATUS FOR OPENING AND CLEANING COTTON OR LIKE FIBROUS MATERIAL

Application filed September 29, 1930, Serial No. 485,190, and in Great Britain October 10, 1929.

This invention concerns hopper bale breakers, hopper bale openers, hopper feeders, and like apparatus used in the cotton trade.

In this class of apparatus the fibre is carried by a substantially horizontal lattice to an upright or inclined spiked lattice or spiked roller or rollers and wherein the material lifted is acted upon by a rotating flapper or flappers, or an additional spiked lattice or kindred devices and the surplus or excess returned back to the hopper.

The delivery end of the upright spiked lattice is stripped by one or more rotating flappers or beaters or mechanical appliances.

All these flappers are intended to act on the cotton mechanically and they generate dust. It is common for the flappers at the delivery side of the lattice to work over grid structures with the idea of getting rid of dust and dirt, before the cotton is conveyed on by a pneumatic system or by mechanical devices.

In actual practice there is much turmoil in the interior of the hopper structure and much dust is there liberated on both sides of the upright lattice, and it is common to enclose or partly enclose the hopper structure or bin, and, by provision of fans or grids over the hopper to endeavour to get rid of the dust from the material handled in the machine.

In such schemes it is difficult to extract dust effectively, without extracting cotton.

As at present constructed the spiked lifting lattice or its equivalent, and both clearing and surplus returning flappers or operative contrivances, together with their housings, constitute obstructions within the machine to the free passage of air from feed to delivery.

We consider that such conditions are disadvantageous to the effective removal of dust and our invention contemplates the re-arrangement of the flappers or operative contrivances and air ways around them in such a manner as to permit a free flow of air through or about the flappers themselves and

around them and also the provision of additional air ways external to or divided off from the existing hopper structure either over the top or around the side or both in such a manner as to short-circuit the obstructing spiked lattice which together with its surplus returning flappers or the like under existing conditions, in effect, divides the machine into two compartments, in both of which dust is generated, thus allowing air to enter the hopper at the feed end, permeate and pass through the machine, together with the cotton and to extract the air charged with dust during its passage, at the delivery end of the machine, and to separate and permanently remove such dusty air from contact with the cotton, by means of ordinary dust cages or high speed filtering cages or other means which automatically separate the dust from the fibre.

The cleaning and conveying operations are assisted by the action of a cage device, preferably a high speed cage, which collects and removes the dust, and liberates the cotton collected on the cage.

The accompanying drawings illustrate two arrangements which embody the improvements already clearly suggested, and, in such drawings:—

Fig. 1 is a sectional elevation of a hopper feeder combined with a high speed cage, a beater contrivance being shown behind the spiked lifting lattice, and an overhead conduit or passage way leading from the front of the hopper or bin to just over said beater contrivance.

Fig. 2 shows a plan view of Fig. 1 drawn partly in section.

Fig. 3 is a sectional elevation illustrating a varied construction wherein the conduits or ducts are combined in or with the sides of the hopper and deliver the short-circuited dust laden air to the rear part of the hopper opener axially of the beater contrivance arranged behind the lifting spiked lattice.

Fig. 4 shows a plan of Fig. 3 drawn partly in section.

Fig. 5 indicates over-head and lateral conduit provision.

5 In the example Fig. 1, the front or feed part of the hopper is marked *a* and the rear part *b*, the conveying lattice *c*, spiked lifting lattice *d* and revolving flapper or regulating contrivance *e*. Behind the upper part of the 10 spiked lifting lattice *d* is shown located a revolvable beating contrivance *f* which is indicated as working over grid bars *f'*, and which beater operates in the rear part *b* of the hopper feeder, which rear part *b* is closed 15 in by plates or otherwise top and bottom, to produce a wide chamber leading to the coupled high speed dust cage *g* to be later mentioned.

Leading from the front *a* of the hopper or 20 bin we arrange a canopy-like conduit *h* comprising an upper bent wall *h'* and a lower spaced wall *h''* supported by a cross-tie *h''* or otherwise, the ends of the canopy-like conduit being conveniently the end walls of the hopper 25 per structure.

Such canopy-like conduit is open at the inlet end *h⁴* and the outlet end *h⁵* immediately over the beater *f* or like revolvable contrivance. The high speed cage *g* works close to 30 the enclosed rear part *b* of the hopper feeder and is housed in a casing *g'*, and there is shown a closing roller *g²*, and an air trunk *g³* along which the cotton liberated by the cage *g* is conveyed in clean air in manner akin to 35 what is described in U. S. application Serial No. 370,077 filed June 11, 1929. A fan *i* is shown located over the hopper feeder and discharging along the pipe *i'*, trunks *i''* connecting the casing of the high speed cage *g* 40 to the pipes *i''* leading to the fan casing.

When the hopper feeder is at work, the rapidly revolving beater *f* operating closely to the delivery end of the canopy-like conduit *h* and the suction through the high speed 45 cage *g*, induces a considerable proportion of dusty air from the turmoil in the hopper front *a* to pass right away along conduit *h*, whereby the flapper contrivance *e* and top of the spiked lifting lattice *d* is avoided. As a 50 consequence considerable dirt, etc., is short-circuited along with some portion of cotton, which latter however reaches the beater *f* and joins the main body of the opened cotton ready to pass through the rear portion 55 *b* of the hopper feeder to the cage *g*. In addition to short-circuiting and getting rid of dirty air, the conduit *h* allows the cage *g* to obtain an adequate-supply of air for its proper working.

60 In the modified scheme shown by Figs. 3 and 4, instead of an over-head or canopy-like conduit, we show side outlets *h⁶* cut in the walls of the hopper and there are provided outside conduits or channels *h⁷* which lead into the rear structure *b* of the hopper, such

conduits or channels communicating axially with the beater contrivance *f* shown working over the bars *f'*. In this case the beater used is of a mixed flow fan type inducing a flow of air axially and discharging radially. 70 The rest of the construction is similar to that shown by Figs. 1 and 2, and the parts are marked with like reference letters.

In this example a considerable quantity of dirt laden air from the front compartment *a* 75 of the hopper is, during working of the apparatus, short-circuited and reaches the beating contrivance *f*, and the high speed cage *g* can obtain an adequate supply of air induced by the fan *i*.

We might provide both an overhead conduit, and a side duct or ducts in the same hopper apparatus, as will be apparent, and as is clearly suggested by Fig. 5.

By our improvements, use is made of air 85 suction in hopper openers by provided air suction devices such as cages, for the withdrawal of dust from the front and back of the upright spiked lattice. We utilize a suction device in such manner that the supply air 90 therefor is drawn substantially out of the hopper structure, and said air is caused to pass directly and indirectly over or adjacent to or in connection with the rear part of the spiked lifting lattice in manner to remove 95 or convey dust and dirt, and so that same may travel along with the opened cotton to cage devices which act to automatically separate the dust and dirt to convey same away and to liberate and deliver the cleaned fibre. 100

We claim:—

1. A hopper bale opener, hopper feeder or like apparatus for opening and cleaning cotton and having front compartment and substantially closed rear compartment to 105 said hopper and cotton lifting and regulating contrivances and a beater in the rear of the lifting contrivance, a revolvable dust cage device combined with the substantially closed rear compartment, and air suction means, 110 and with suction-affected conduit provision leading from the front compartment of the hopper to the beater in the rear compartment, and with dirt outlet below the revolvable beater, the rear compartment being enclosed 115 between revolving beater and the revolvable dust cage and with dust trunk connection between the revolvable dust cage and the suction means, and whereby the operative treatment is partly pneumatic and partly mechanical as set forth.

2. A hopper bale opener, hopper feeder, or like apparatus for pneumatically and mechanically opening and cleaning cotton, wherein there is combined a front compartment, a substantially closed rear compartment, and cotton lifting and regulating means and a revolvable beater behind the lifting contrivance and with suction-affected 125 conduit provision directly connecting the 130

front compartment with the closed rear compartment, the latter having a dirt outlet and a combined revolvable dust cage with damper at the delivery end of the substantially closed 5 rear compartment, and end outlet leading to a dirt conveying trunk in connection with which there is combined a suction appliance, all whereby dust, dirt, and some fibre can be short circuited to the beater in the rear compartment, the dust and cotton to be separated, 10 and to enable the revolvable dust cage to receive an adequate supply of air as related.

In testimony whereof we have signed our names to this specification.
